US0D1015863S

(12) **United States Design Patent** (10) **Patent No.:** **US D1,015,863 S**
(45) **Date of Patent:** **** Feb. 27, 2024**

(54) **FASTENING DEVICE**

(71) Applicant: **Nord-Lock Switzerland GmbH**, St. Gallenkappel (CH)

CN 3326275 * 10/2003
CN 300795614 * 6/2008

(Continued)

(72) Inventor: **Jérôme Munda**, Sathonay-Camp (FR)

Primary Examiner — Sheryl Lane

(73) Assignee: **Nord-Lock Switzerland GmbH**, St. Gallenkappel (CH)

Assistant Examiner — Ieisha N Price

(74) Attorney, Agent, or Firm — Tucker Ellis LLP

(**) Term: **15 Years**

(21) Appl. No.: **35/515,634**

(57) **CLAIM**

(22) Filed: **Nov. 3, 2022**

The ornamental design for a fastening device, as shown and described.

(80) **Hague Agreement Data**

Int. Filing Date: **Nov. 3, 2022**

Int. Reg. No.: **DM/224793**

Int. Reg. Date: **Nov. 3, 2022**

Int. Reg. Pub. Date: **Nov. 18, 2022**

DESCRIPTION

(30) **Foreign Application Priority Data**

May 20, 2022 (EM) 009031750-0001

May 20, 2022 (EM) 009031750-0002

(Continued)

The patent or application file contains at least one drawing executed in color. Copies of this patent or patent application publication with color drawing(s) will be provided by the Office upon request and payment of the necessary fee.

1.1: Perspective view.

1.2: Front view.

1.3: Rear view.

1.4: Left view.

1.5: Right view.
